UNITED STATES PATENT OFFICE.

GEORGE R. MURRAY, OF CHAMBERSBURG, PENNSYLVANIA, ASSIGNEE TO CHAMBERSBURG ENGINEERING COMPANY, OF CHAMBERSBURG, PENNSYLVANIA, A CORPORATION OF PENNSYLVANIA.

DROP HAMMER.

Application filed October 24, 1921. Serial No. 509,844.

My invention relates to improvements in drop hammers and like machines, and more particularly to improvements in the control mechanism of said hammers.

One object of my invention is to provide a control mechanism from which the excessive shocks commonly found in the usual forms of control mechanism are eliminated, thereby materially reducing the wear upon and increasing the life of the various elements.

Another object of the invention is to provide a control mechanism in which the adjustment of the ram stroke is greatly facilitated.

A still further object is to provide means whereby wear developing in the elements may be readily taken up by adjustment.

The invention further contemplates the provision of means for manually controlling and limiting the stroke of the hammer between the automatic stops, thereby permitting short rapid strokes at the will of the operator without interruption in the operation of the hammer for readjustment of any of the control settings.

In the attached drawings:

Figure 1 is a front elevation of a board drop hammer equipped with control mechanism made in accordance with my invention,

Fig. 2 is a side elevation of the hammer, and

Fig. 3 is a section on the line 3—3, Fig. 1, showing details of the control lever and the contact dogs.

With reference to the drawings, 1 indicates the anvil of a board hammer, 2, 2, the side frames, and 3 the upper housing, in which are mounted the feed rolls 4, 4, which operate in conjunction with the board 5 to elevate the ram 6, which latter travels between vertical guides 2^a, 2^a, on the said frames 2, 2. In the present instance, the feed rolls are clamped together upon the board, and are separated to release the board in the usual manner by means of the usual eccentric mechanism and a so-called front rod 7 which constitutes the operating member for said mechanism. The mechanism so far described is standard, and will be well understood by all acquainted with the art.

The front rod 7, which may be termed

the operating member, extends downwardly from the housing 3 in the usual manner, but has at the lower end a longitudinal slot 8 through which extends a pin 7^a in the end of one arm of a bell crank lever 9 pivotally secured at 10 to one of the side frames 2. The other arm of the lever 9 is secured by means of a link 11 to the upper end of a control lever 12 pivotally mounted intermediate its ends upon a pin 13 secured on the side frame 2. A spring 14 is in the present instance mounted upon the pin 13, and is confined between a nut 15 on the threaded outer end of the pin and the side of the lever 12, said spring tending to dampen the motion of the lever around its pivot.

Adjustably secured, one at each end of the control lever 12, is a wedge-shaped dog, 16 and 17 respectively, said lever being so disposed that normally one or other of the dogs 16 or 17 extends into the path of the ram 6 as it reciprocates between the guides 2^a. In the present instance, the dogs 16 and 17 are secured to the control lever 12 by means of bolts 18, 18, which latter extend through the said dogs and through suitable longitudinal slots in the control lever, this securing means providing means for easy and quick adjustment of the dogs longitudinally of the control lever.

As clearly shown in Fig. 1, the upper and lower edges of that side of the ram 6 to which the said dogs are presented are beveled, as indicated at 19 and 20, these beveled edges being adapted to engage the correspondingly inclined faces of the dogs 16 and 17 respectively.

Pivotally mounted at 21 to the side frame 2 is a lever 22, one end of which underlies and is adapted to engage the lower end of the front rod 7, the opposite end of the lever being connected by means of a rod 23 to a lever 24 pivotally secured at 25 to the said side frame. The lever 24 is also connected by means of a rod 26 and a chain or similar flexible connector 27 to a treadle 28 pivotally mounted upon a rod 29 mounted near the base of the anvil 1, said treadle having an arm 29 which is connected as shown in Fig. 2 to one of a pair of board clamps 29^a which retain the board and ram in the elevated position when it is desired to stop the machine with the ram in an ele-

vated position, the treadle 28 constituting the usual clamp control. The lever 24 has therein an aperture 30 which, when the lever is in a depressed position, is adapted to correspond in position with an aperture 31 in the side frame 2, and a pin 32 is provided for insertion in the said apertures whereby the lever may be retained in the depressed position. The lever 24 and rod 23 are supported in a normal elevated position by means of a spring 22^a suspended from the side frame 2 and having the lower end attached to the outer end of the lever 22. The operation of the machine is as follows: We will suppose that in the drawings the ram is shown retained in an elevated position by means of the aforementioned clamps. These clamps are released in the usual manner by depressing the treadle 28. When the ram is in the elevated position, the upper portion of the control lever 12 is shifted outwardly by contact with the side of the ram, as clearly illustrated, the outward movement of the upper portion of said lever having the effect of oscillating the lever 9 so as to elevate the pin 7^a and consequently the front rod 7, elevation of the front rod releasing the board from the rolls in the usual manner. With the depression then of the treadle 28, the ram is permitted to drop, and as it nears the bottom of its stroke, the beveled edge 19 comes into engagement with the inclined surface of the dog 16 which, by reason of the outward movement of the upper end of the lever 12 and the consequent inward movement of the lower portion of the lever, has been shifted into the path of the ram. Engagement of the dog 16 by the ram has the effect of shifting the lower portion of the lever outwardly and the upper portion inwardly, thereby oscillating the lever 9 in such manner as to carry the pin 7^a downwardly, thereby releasing the front rod 7, which latter falls by gravity and causes the feed rolls to grip the board to again effect elevation of the ram. In the upward travel of the ram, the beveled edge 20 engages the inclined face of the dog 17, thereby shifting the upper portion of the lever 12 outwardly and releasing the rolls in the aforesaid manner to again permit the ram to fall, the cycle being repeated. As previously stated, the hammer is stopped with the ram in an elevated position by releasing the treadle 28, and by means of the lever 22, the rod 23, and the lever 24, it is possible to stop the machine with the ram in the depressed position, this being accomplished by forcing the lever 24 downwardly and inserting the pin 32 through the aperture 30 and the aperture 31 to retain the said lever 24 in the depressed position, the depression of the lever 24 having the effect, through the lever 22, of elevating the front rod 7 independent of the control lever 12,

and thereby preventing the engagement of the board by the feed rolls. The movement of the front rod 7 independent of the control lever 12 is provided for in the slot 8 through which the pin 7 extends. To start from this position of the ram, the pin 32 is removed, thereby permitting the front rod 7 to drop by gravity, this movement of the lever having the effect of raising the lever 24 through the lever 22 and the rod 23. Due to the flexible connector 27 between the lever 24 and the treadle, this movement of the lever 24 does not affect the treadle.

It should be noted that the flexible connector 27 is sufficiently long to permit depression of the treadle into the clamp-releasing position without affecting the position of the lever 24, and further, this connector 27 should be of such length as to permit depression of the lever 24 by depression of the treadle beyond the normal extent for releasing the said clamps. In this manner, when the board and ram are on the upstroke, an additional pressure of the treadle beyond the normal running position will, through the chain 27, rod 26, lever 24, and rod 23, oscillate the lever 22 in such manner as to elevate the front rod, and so shift the rollers to free the board, which with the ram returns to the bottom of its stroke. In this manner, the stroke of the ram may be controlled within the limits of the dogs entirely independent of the normal control elements and without adjustment of any part, this being particularly desirable for sprue drawing and for series of short blows.

It will be apparent that the extent of the stroke of the ram and the high and low positions of the stroke may be controlled by adjusting the dogs 16 and 17 upon the control lever 12.

The advantages of this form of control over the forms now in common use are many. By means of the pivoted control lever 12, the cam-like dogs and the rigging which connects the lever to the front rod 7, the operation of reciprocating the front rod 7 is practically shockless, and as a consequence wear in the front rod and in the roll releasing lever is reduced to a minimum. The automatic action of the control mechanism is extremely smooth, and it will be noted that the downward movement of the front rod 7 to permit the rollers to move against the board is controlled by the downward movement of the pin 7^a, which latter movement is in turn controlled by the outward movement of the lower end of the control lever 12, as effected by the cam-like action between the ram and the inclined surface of the dog 16, this action eliminating much of the shock commonly experienced in the downward movement of the front rod, and eliminating practically all of the wear at the lower end of the rod. This compara-

tively gentle and progressive movement of the parts is also had at the top of the stroke when the ram engages the inclined surface of the dog 17, the shock at this point also being materially reduced. The reduction in the wear of the parts consequent to this aforescribed action greatly reduces, and in fact practically eliminates breakage of the parts and the attendant interruptions in the operation of the machine.

It will be noted further that practically all of the wear in the control apparatus occurs on the surfaces of the dogs 16 and 17, and further that this wear is substantially uniform over the entire length of the inclined surfaces of the dogs which are engaged by the ram. A full compensation of the wear occurring in the dogs can be accomplished by merely adjusting the dogs inwardly towards the center of the lever 12. It will also be noted in this connection that the adjustment of the dogs on the lever 12 is an extremely simple one, being accomplished entirely by manipulation in each case of the two retaining bolts, and that consequently all complication in adjusting the control to give strokes of different lengths is eliminated.

A further extremely important feature of the invention is the provision for controlling the stroke of the ram independent of the normal automatic control, this independent control being accomplished as described by means of the treadle 28. This permits a shortening of the stroke at the will of the operator without reference to the automatic control elements and without the necessity for adjusting these elements to the desired short stroke. Where a short light blow is desired or a series of short rapid blows, this feature will be found extremely valuable, as hitherto blows of this sort have required a readjustment of levers and dogs, with a consequent readjustment of these elements to positions giving the normal stroke.

I claim:

1. In a machine of the type specified, the combination with an actuated element and actuating mechanism therefor, of a substantially vertically reciprocatory control element connected with the actuating mechanism, an oscillatory element adapted to receive its motion by engagement with the actuated element in its travel, and means interconnecting the control element and the said oscillatory element whereby the oscillatory movement of the latter effects vertical movement of the control element.

2. In a machine of the type specified, the combination with an actuated element and actuating mechanism therefor, of automatic means for alternately connecting and disconnecting the said element from the ac-

tuating mechanism, means independent of said automatic means for disconnecting the said actuated element from the actuating mechanism, a lever for operating the independent control means, and means permitting partial advancement of the lever toward operating position without affecting the independent control means.

3. In a machine of the type specified, the combination with an actuated element and actuating mechanism therefor, of automatic means for alternately connecting and disconnecting the said element from the actuating mechanism, means independent of said automatic means for disconnecting the said actuated element from the actuating mechanism, an operating element flexibly connected with the independent control, and mechanism for gripping and anchoring the actuated element operatively connected with the said operating element.

4. In a machine of the type specified, the combination with a vertically reciprocatory element and actuating mechanism therefor, of means for operatively connecting and disconnecting the element and the actuating mechanism, gripping and supporting mechanism for said element, and an operating member having connection both with said connecting and disconnecting means and with the element gripping mechanism.

5. In a machine of the type specified, the combination with a vertically reciprocatory element and actuating mechanism therefor, of means for operatively connecting and disconnecting the element and the actuating mechanism, gripping and supporting mechanism for said element, an operating member, means including a flexible element connecting the operating member with the connecting and disconnecting means, and means for rigidly connecting the operating member with the element gripping mechanism.

6. In a board drop hammer, the combination with elevating rolls, of means for actuating the rolls to grip and release the board, board clamping means, and a common control lever connected with both said gripping and clamping means adapted in an elevated position to apply the clamping means, in an intermediate position to release the clamp, and in a depressed position to release the gripping rolls.

7. In a machine of the type specified, the combination with an actuated element and actuating mechanism therefor, of control means for the mechanism comprising a substantially vertically movable element, mechanism for elevating the said vertically movable element, and means operatively associated with said mechanism for retaining the element in elevated position.

GEORGE R. MURRAY.
